UNITED STATES PATENT OFFICE.

VICTOR WILLOUGHBY, OF RIDGEWOOD, NEW JERSEY, ASSIGNOR TO AMERICAN CAR AND FOUNDRY COMPANY, OF NEW YORK, N. Y., A CORPORATION OF NEW JERSEY.

MINE CAR.

Application filed May 11, 1925. Serial No. 29,462.

The accompanying drawings illustrate the preferred form of the invention, though it is to be understood that the invention is not limited to the exact details of construction shown and described, as it is obvious that various modifications thereof within the scope of the claims will occur to persons skilled in the art.

In said drawings:

10 Fig. 1 is a side elevation of a mine car constructed in accordance with this invention, parts being broken away to show a journal box and draw bar in section;

15 Fig. 2 is a vertical transverse section taken on the line 2—2 of Fig. 3; and

15 Fig. 3 is a top plan view of the car shown in Fig. 1, parts of the floor being broken away to show other parts more clearly.

This invention relates to mine cars and has as an object the provision of a mine car of composite structure, large capacity and low maximum height which shall be of rugged and inexpensive construction. Another object is to provide a car of the type specified having plate girder side sills fastened together to form a rigid frame for the car and reenforced by gusset plates secured to the floor. Another object is to provide a center bumper car of the type specified having a draw bar and buffer beam suitably reenforced at the coupler members and bumpers.

Another object is to provide an improved braking means for a car of the type specified. With these and other objects in view, 35 a mine car, as shown in the drawings, constructed in accordance with this invention comprises angles 1 having the flanges 2 horizontal and projecting inwardly and the flanges 3 vertical and projecting upwardly. 40 The angles 1 are connected at their ends by angles 4 having the flanges 5 vertical and projecting downwardly and the flanges 6 horizontal and projecting toward the center of the car and secured at their ends to the horizontal flanges 2 of the angles 1 by rivets 7. At their centers, the angles 1 are connected by an angle tie 8, similar to the angles 4, and intermediate the center tie 8 and the angles 4 the angles 1 are connected by ties 9 of Z-shape having their webs 10 vertical and their top flanges 11 connected to the horizontal flanges 2 of the angles 1 by rivets 12.

55 The horizontal flanges 2 of the angles 1

are partly cut away providing openings in which are fitted the offset portions 13 of plates 14 which are secured to the adjacent ends of the horizontal flanges 2 of the angles 1 by rivets 15. The offset portions 13 of the plates 14 are shaped to receive the tops of journal boxes 16 which are fastened to the angles 1 and plates 14 by bolts 17 which engage in alined openings in the horizontal flanges 2 of the angles 1, plates 14 and 65 flanges 18 of the journal boxes 16. In the journal boxes 16 are mounted axles 19 having wheels 66 fixed thereon.

Mounted on the angles 4 and ties 8 and 9 and extending along the longitudinal center of the car and beyond each of the angles 4 is a draw or buffer beam 20 of inverted U-shape and having outwardly projecting horizontal flanges 21 riveted to the horizontal flanges of the angles 4 and ties 8 and 9. 70 Also mounted on the horizontal flanges of the angles 4 and ties 8 and 9, upon opposite sides of the buffer beam 20 are planks 22 which, together with the web 23 of the buffer beam 20 form the car floor and are fastened to the horizontal flanges of the angles 4 and ties 8 and 9 by bolts 24. The planks 22 extend beyond the angles 4 gradually increasing in length from the angles 1 to the buffer beams 20 to form a center bumper for 85 the car. The planks adjacent the angles 1 and buffer beam 20 are gained along an edge to fit the angle and beam flanges 2 and 21, respectively, and at the wheels 66, the planks 22 are cut away to provide wheel openings 90 25 which are covered by wheel hoods 26 bolted to the planks 22.

At each end there is provided a bumper 27 of substantially U-shape which fits over the ends of the buffer beam 20 and planks 95 22 and extends for a suitable distance on each side of the buffer beam 20. Each bumper comprises a top plate 28 which extends over the adjacent angle 4, a bottom plate 29 which extends to the adjacent angle 100 4 and is spaced from the top plate a sufficient distance to permit of the insertion of the filler 30 between the plate 29 and the bottoms of the planks 22 and buffer beam 20. The top and bottom plates 28 and 29 of the bumper 27 are connected by a face plate 31 which is curved slightly to fit the ends of the planks 22. At its ends, the buffer beam web 23 is reenforced by plates 32 and has riveted thereto the coupler members 33 110

which are bent upwardly so as to space the outer ends of the coupler members from the bumpers 27 to leave openings for the usual coupling links. The coupler members 33 are provided with openings 34 to receive the coupling pins 35 which extend through openings provided in bumpers 27, buffer beam 20 and fillers 30.

To the outer faces of the upwardly projecting flanges 3 of the angles 1 are riveted the plates 36 provided with rolled-over top edges 37 and forming the sides of the car. The car sides are connected at their ends by the corrugated plates 38 forming the car ends and having rolled over top edges 39 and openings 40 to receive the coupler members 33. The end plates 38 are fastened to the car floor by bolts 41 which engage the planks 22 and the angles 4 and the inwardly projecting flanges 42 on the plates 38 and are fastened to the car sides by rivets 43 which engage the plates 36 and the inwardly projecting flanges on the plates 38. Angles 44 riveted to the plates 36 and 38 aid in securing the car ends and sides together. The car sides are braced at the ties 8 and 9 by triangular gusset plates 45 which are flanged on all edges and are secured to the car sides by rivets 46 which engage the flanges 47 and the plates 36 and are fastened to the car floor by bolts which engage the flanges 48, fillers 49, planks 22 and the horizontal flanges of the ties 8 and 9.

It will be noted that the angles 1 and the plates 36 together form plate girder side sills, the angles 1 forming the bottom chord and the rolled over upper edge 37 of the plate 36 forming the top chord. The end plates 38 also form plate girders, the flanges 42 forming the bottom chord and the rolled over edges 39 forming the top chord. The end plates 38 aid in supporting the ends of the planks 22 and transmit the load to the plate girder side sills which through the plates 14 transmit the load directly to the journal boxes 16. The load is also transmitted to the side sills from the planks by the angles 4, ties 8 and 9 and gusset plates 45.

It will also be noted that the metal parts 50 are secured together by rivets and the planks are secured to the metal parts by bolts so as to permit of rapidly replacing the planks. In this connection it will be noted that the fillers 49 will provide clearance between the flanges 48 of the gusset plates 45 and planks 22 so that the gusset plates will not interfere with the withdrawal of the planks.

Secured to the horizontal flanges 2 of the angles 1 by bolts 50 which extend through the planks 22 of the floor are brackets 51 in which is journaled a shaft 52 having, at one end, a crank arm 53 connected by rod 54 to a brake lever 55 pivotally mounted on bracket 56 secured to the side sill flange 2. The lever 55 has a lug 57 positioned to en-

gage with the teeth 58 of angle 59 carried by bracket 60 to hold the lever 55 in adjusted position. Crank arms 61 carried by shaft 52 are pivotally connected to equalizers 62 which have their ends connected to brake bands 63 fitting over the wheels 66 and connected to the brackets 64 carried by the horizontal flanges 65 of the ties 9.

What is claimed is:

1. In a mine car, side sills forming the car side walls, end angles and ties connecting said sills, a floor carried by said end angles and ties, end walls connecting said side walls and having bottom flanges lapping and being connected with said floor. 75
2. In a mine car, angles having horizontal flanges provided with openings to receive journal boxes, plates fastened to said flanges and having portions bent to receive the journal boxes and fitting into said openings 80 and means securing said journal boxes to said flanges and plates. 85
3. In a mine car, flanged side sills having openings in the flanges to receive the journal boxes, a floor recessed to receive the journal boxes, plates fixed to said side sills at said openings and projecting beyond said flanges, said plates being shaped to receive the journal boxes and fitting in the recesses in said floor, journal boxes fitting said plates and 90 means securing said floor, side sills, plates and journal boxes together. 95
4. In combination, a car bottom, angles extending longitudinally of the edges thereof and each having one flange disposed in a horizontal plane and provided with spaced openings, sill plates attached to the horizontal flanges and each having an offset portion projecting through one of the openings, and journal boxes attached to the horizontal 100 flanges with their tops accommodated in said offset portions. 105
5. In a mine car, end angles, a floor carried by said angles, bumpers engaging said floor, end walls mounted on said floor and 110 bumpers and means securing said end walls to said floor and bumpers. 115
6. In a mine car, end angles, a floor carried by said end angles, bumpers carried by said floor and secured to said end angles and 115 fillers between said floor and bumpers, said fillers bearing against said end angles. 120
7. In a mine car, end angles, a floor carried by said angles, bumpers carried by said floor, end walls mounted on said floor and bumpers and means detachably connecting said end walls, bumpers and end angles. 125
8. In a mine car, side sills, end angles and ties connecting said sills, a channel shape buffer beam connecting said end angles and having a web forming part of the car floor and wooden floor sections between said buffer beam and side sills having wheel openings therein. 130
9. In a mine car, flanged side sills, end

angles and ties connecting said sills, a buffer beam connecting said end angles and forming part of the car floor and wooden floor sections between said buffer beam and side sills having wheel openings therein, said side sill flanges and wooden floor sections being cut away to form recesses for the journal boxes.

10. In a mine car, flanged side sills forming the car side walls, end angles and ties connecting said sills, wooden floor sections carried by said sills, angles and ties, flanged end walls connecting said side walls and secured to said floor sections and end angles and flanged gusset plates connecting said side walls to said floor sections and the flanges of said ties.

11. In a mine car, journal boxes, plate girder side sills carried directly on said journal boxes, end ties comprising angles each connected to said side sills, and a floor having the end portions thereof carried by said end ties.

12. In a mine car, journal boxes, plate girder side sills mounted on said journal boxes, end plates and ties each connecting said sills, said end plates having bottom flanges formed thereon, and a floor carried by the flanges on said end plates and by the ties.

13. In a mine car, journal boxes, plate girder side sills forming the side walls of the car and mounted on said journal boxes, a floor, gusset plates connecting said side sills and floor and extending to the top of the side sills, and end plates carried by said side sills and having bottom flanges formed thereon to overlap and support the ends of said floor.

14. In a mine car, journal boxes, plate girder side sills mounted on said journal boxes, means comprising end angles and end

plates each connecting said side sills, a load sustaining floor carried by said connecting means and bracing means comprising gusset plates for connecting said floor and side sills and extending to the top of the side sills.

15. In a mine car, journal boxes, plate girder side sills forming the sides of the car and mounted on and over said journal boxes, transverse members connecting said side sills, a floor carried by said members and gusset plates connecting said side sills and floor and extending to the top of said side sills.

16. In a mine car, journal boxes, plate girder side sills mounted on said journal boxes and forming the side walls of the car, end angles and ties connecting said sills, end walls connected to said side sills and having bottom flanges thereon and a floor carried by said flanges, ties, and end angles.

17. In combination, a car bottom, angles extending along the edges of the car bottom and each having one flange disposed below the latter and provided with spaced openings, a sill plate at each opening and having an offset portion projecting through the latter, a journal box beneath each sill plate and having its top accommodated in one of the offset portions, and means for securing the journal boxes and sill plates in place.

18. In a mine car, side sills, end angles connecting said side sills, a floor supported on said end angles, a buffer beam extending from end to end of the car and secured to said end angles, said buffer beam having a portion thereof forming part of the floor, coupler members connected to said buffer beam and bumpers connected to said buffer beam and end angles.

In witness whereof I have hereunto set my hand.

VICTOR WILLOUGHBY.
